SHEAR

Frederick E. Munschauer, Jr., Buffalo, N. Y.

Application September 7, 1950, Serial No. 12,088

Term of patent 14 years

(Cl. D55—1)

To all whom it may concern:

Be it known that I, Frederick E. Munschauer, Jr., a citizen of the United States, residing at Buffalo, State of New York, have invented a new, original, and ornamental Design for a Shear, of which the following is a specification, reference being had to the accompanying drawing, forming a part hereof.

Fig. 1 is a perspective view taken generally from the front of a shear showing my new design; and

Fig. 2 is a perspective view taken generally from the rear thereof.

I claim:

The ornamental design for a shear, as shown.
FREDERICK E. MUNSCHAUER, JR.
